ELECTRIC GASEOUS DISCHARGE LAMP

Carl Herzog, Belleville, N. J.

Application January 24, 1945, Serial No. 574,306

9 Claims. (Cl. 176—126)

1

My invention relates to electric gaseous discharge lamps, and to a method of producing the same.

An important object of the invention is to provide a glass disc or base for closing the end of the glass tube or envelope, and having the leads embedded therein and also provided with a metal ring which may be heated by electrical induction and which will in turn heat and plasticize the glass tube or envelope.

A further object of the invention is to provide a hot electrode discharge lamp which may be vacuum sealed by employing internal and external heating elements heated by electrical induction.

A further object of the invention is to provide an electric discharge lamp having the glass tube welded to a metal part of the disc or base, in a secure manner, overcoming tendency to breakage.

A further object of the invention is to provide an electric discharge lamp which will lend itself to production by a simplified method of vacuum sealing.

Other objects and advantages of the invention will be apparent during the course of the following description.

In the accompanying drawings forming a part of this application and in which like numerals are employed to designate like parts throughout the same,

Figure 1 is a central vertical longitudinal section through a tubular electric discharge lamp, showing its ends held within operating units, parts in elevation,

Figure 1^a is a transverse section taken on line 1^a—1^a of Figure 1.

Figure 2 is a central longitudinal section through one end of the lamp, showing the glass welding step,

Figure 3 is a similar view showing the glass severing step,

Figure 1^b is a transverse section taken on line 1^b—1^b of Figure 3.

Figure 4 is a central longitudinal section through the completed electric discharge lamp, parts in section,

Figure 5 is a central longitudinal section through one end of the discharge lamp embodying a modified form of the invention, prior to the glass welding step,

Figure 6 is a central longitudinal section through the completed electric discharge lamp, embodying the modified form of the invention, parts broken away,

2

Figure 6^a is a transverse section taken on line 6^a—6^a of Figure 6.

Figure 7 is a central longitudinal section through one end of a third modified form of lamp embodying my invention and prior to the welding step,

Figure 8 is a central longitudinal section through one end of the completed electric discharge lamp embodying the third form of the invention, parts in elevation,

Figure 9 is a similar view of the opposite end, further parts in section, and,

Figure 8^a is a transverse section taken on line 8^a—8^a of Figure 9.

15 In the drawings, wherein for the purpose of illustration are shown preferred embodiments of my invention, the numeral 10 designates a cylindrical glass tube, constituting the envelope of the hot electrode fluorescent lamp. This tube

20 may be of any suitable diameter and length. The inner surface of the tube is covered or coated with a coating composition 11 containing a finely divided luminescent or fluorescent material, and this coating is dried. I may employ the coating

25 composition disclosed in the patent to T. M. Cortese, 2,318,060, and this coating may be applied in accordance with the method disclosed in the Cortese patent. The tube 10, Figure 1, has the fluorescent coating composition 11 of the 30 Cortese patent extending to points 12, the end portions 13 and 14 of the tube 10 having the coating removed and being clean or uncoated.

An electron emitting device 15 is arranged within each end portion of the glass tube 10, and 35 is held therein in spaced concentric relation prior to the glass welding, and while the interior of the glass tube is under vacuum. Each device 15 comprises a relatively thick and strong cylindrical disc or base 16, preferably formed of glass. This

40 disc or base has stout leads 17 embedded therein and extending axially through the same and having a vacuum tight joint therewith. At their inner ends, these leads 17 carry a hot or glow electrode 18. The hot electrode may comprise a 45 coiled tungsten wire, coated with one or more of the alkaline earth oxide. This form of hot electrode for an electric discharge lamp is shown in Patent 2,322,224 and Patent 2,067,746. Any other suitable type of hot electrode may be employed.

The numeral 19 designates a cylindrical retainer which is made of a special commercial chrome-iron alloy which has the same expansion coefficient as glass. This retainer includes an 55 outer ring 20, of smaller diameter than the tube

10 and an inner ring 21, these rings being connected by an end 22. The glass base 16 is arranged within and welded to the inner ring 21 and has a vacuum tight joint therewith.

Each device 15 is supported, during the vacuum period, by metal holders 23, having split resilient sockets 24, for holding the outer ends of the metal leads 17 and having detachable clamping engagement therewith. The holders 23 are mounted upon and insulated from the ends 25 and 26 of operating units 27 and 28.

The numeral 29 designates a cylindrical insulating disc, made of "Bakelite" or the like and having two tubular metal terminals 30 riveted thereto. These tubular terminals receive the outer ends of the leads 17 after the insulating disc is pressed into the recess 31 and the tubular terminals are then squeezed to the leads 17. The disc 29 has a pressed fit in the recess 31. The disc 29 is placed in position after the glass welding and severing operations.

In the practice of the method for producing the electric discharge lamp, the tube 10 is vertically supported by means of a clamp 32 or the like and the opposite ends of the tube are open. The upper end of the tube 10 is inserted into the operating unit 28 and its lower end into the operating unit 27. These operating units are identical to the operating units 19 and 20 of my co-pending application for "Method of and Apparatus for making cold cathode fluorescent lamps or the like," filed March 7, 1944, Serial No 525,446, which issued December 25, 1945, as U. S. Patent 2,391,573, except that the holders 23 are different. The devices 15 are supported in the end portions of the tube 10 by the holders 23. The two electron emitting devices 15 are therefore supported within the end portions of the tube 10 and the outer rings 20 of the retainers are in spaced concentric relation to the tube. With the parts thus arranged, the dried coating 11 may be baked by circulating heated air through the tube 10, as disclosed in my said co-pending application, or the baking may be effected in an oven prior to the arrangement of the tube 10 in the operating units. The lower end of the tube 10 is now placed in communication with a source of vacuum and the tube evacuated and this vacuum is held on the tube while its opposite ends are open. Each electrode 18 may be connected with the opposite poles of a source of current. This is done in the presence of the vacuum and will serve to heat each electrode 18 and drive off undesirable gases or impurities. This heating step is discontinued after a suitable time. The suitable vacuum is still maintained within the tube 10 and a high frequency electric coil A is now brought into position for surrounding the lower end of the tube 10 and the lower retainer 19. A carbon ring B is arranged between the coil A and the tube 10, and ring 20, ring B and coil A are in alignment. When an alternating current is turned on the coil A, current is induced in the exterior ring B and the interior ring 20, and these rings are highly heated. The heat is radiated outwardly from the ring 20 and radiated inwardly from the ring B to the glass tube 10, Figure 2. This glass tube is accordingly heated and plasticized and due to the presence of the vacuum in the tube 10, the heated portion of the tube is drawn inwardly, Figure 2, and contacts with the ring 20 and is welded to the ring. The current may now be turned off from the coil A, while the tube will be severed at the point

32'. The glass tube 10 is welded to the ring 20 to form a vacuum-tight joint therewith.

A small amount of an inert gas, such as argon or neon may now be supplied into the upper end of the tube 10, and after this is done, a measured amount of mercury may be supplied into the upper end of the tube 10 and will drop to the bottom thereof. The gas and mercury may be supplied in the manner disclosed in my said co-pending application.

The tube 10 still has the vacuum therein and another high frequency coil A and another ring B are positioned adjacent to the upper ring 20. Current is now supplied to the upper coil A and the tube 10 is heated and welded to the upper ring 20 and subsequently severed, in the manner described in connection with the lower electrode.

After the glass welding steps are completed, the tube 10 is separated from the operating units 27 and 28 and coils A and rings B, and the discs 29 are pressed into the recesses 31 and have a press-fit therein, and the tubular terminals 30 applied to the outer ends of the leads 17 and pinched thereon.

Figure 4 shows the completed electric discharge lamp. The ends of the glass tube 10 are welded to the metal rings 20 having the same coefficient of expansion as the glass and forming a vacuum-tight joint with the glass tube. The thick glass base 16 carries the leads 17, and the disc 29 adds to the all-over thickness of the base and carries the tubular terminals 30.

In Figures 5 and 6, the leads 17 are embedded in a cylindrical glass base 33, having the all-over desired thickness, since the insulating disc 29 is dispensed with. The leads 17 carry the electrode 18. A metal retainer including a ring 34 is provided, and this ring is formed of a special commercial chrome-iron alloy having the same coefficient of expansion as the glass tube. The base is welded to the ring 34 for forming a vacuum-tight joint therewith and the base 33 has its inner portion 35 molded to project over the end of the ring 34 and is flush with the circumference of the ring 34. The base 33 is secured to the ring 34 before the assembled unit 15 is mounted in the tube 10.

The same method steps are followed in welding the ends of the tube 10 to the rings 34 as described in connection with the first form of lamp. When the tube 10 is welded to the ring 34, Figure 6, there is a glass-to-glass weld at 35a, thus providing a continuous glass surface, which greatly strengthens the construction. All of the method steps recited in connection with the production of the first form of lamp are employed.

In Figures 5 and 6, the numeral 35' designates tubular metal terminals, mounted upon the leads 17, and having their inner ends embedded within 60 and welded to the glass base 33, to strengthen the construction. These tubular terminals are also squeezed to the leads 17.

In Figures 7, 8 and 9, I have shown a third modification of the invention. In these figures 65 the numeral 35b designates a cylindrical glass base having the all-over desired thickness and this base has the leads 17 embedded therein. This base is surrounded by a metal retainer or ring 36, formed of a special commercial chrome-iron alloy, having the same coefficient of expansion as the glass. The base 35b is welded to the metal retainer or ring 36 and the upper end of the base extends beyond the retainer 36 and is molded to provide an end portion 37, extending 70 radially beyond the retainer and also extending 75

axially inwardly over the same for a short distance. This end portion 37 is welded to the retainer or ring 36.

When the end of the tube 10 is welded to the metal retainer or ring 36, the end 37 is also welded to the tube 10 and provides a glass-to-glass weld 38 and a continuous glass surface which serves to strengthen the construction.

Tubular metal terminals 39 receive the leads 17 and have their inner ends embedded within and welded to the glass base 35b. These tubular terminals are squeezed to the leads, and the leads carry the electrode 18.

In the production of the third form of lamp all of the method steps recited in connection with the production of the first form of lamp are used.

The second and third forms of lamps are identical with the first form of lamp, except in the particulars herein pointed out. The same tube 10 with its coating, the same electrodes 18, and the same leads 17 are employed. In each form of lamp, a base is provided which carries the leads and terminals and this base has a wide cylindrical surface or periphery which is welded to the tube 10. This provides a strong construction and the base carries the terminals, and the usual outside insulating cap or base carrying terminals is eliminated. In each form of lamp, the metal carrier or ring has the same coefficient of expansion as the glass base and glass tube.

In the use of the holders 23 in connection with the second and third forms of the invention, the resilient sockets 24 will be somewhat enlarged, for receiving the tubular terminals 35' and 38.

It is to be understood that the forms of my invention herein shown and described are to be taken as preferred examples of the same and that various changes in the shape, size, and arrangement of parts may be resorted to without departing from the spirit of my invention or the scope of the subjoined claims.

Having thus described my invention, what I claim is:

1. An electric discharge device comprising a glass tube having one end open, a glass base, a metal retainer comprising spaced inner and outer rings, the inner ring receiving the glass base which is welded to the inner ring, the outer ring being arranged within the glass tube and having the glass tube welded to it, leads embedded in the glass base, an insulating disc mounted upon the outer face of the glass base, tubular terminals carried by the insulating disc and receiving the outer ends of the leads, and a hot electrode carried by the inner ends of the leads.

2. An electric discharge device comprising a glass tube having one end open, a wide glass base, a metal ring applied to the periphery of the glass base and having the glass base welded to it, the glass base being arranged within the open end of the glass tube and the glass tube welded to the metal ring, leads embedded in the glass base, tubular terminals receiving the outer ends of the leads and having their inner ends welded to the glass base, and a hot electrode carried by the inner ends of the leads.

3. An electric discharge device comprising a glass tube having an opening, a glass base, a metal ring receiving the glass base at its periphery and having the glass base welded to it, the glass base extending beyond one end of the metal ring, the glass base having a substantial width, the glass base being arranged within the glass

tube and the glass tube welded to the metal ring and that portion of the glass base extending beyond the end of the metal ring, leads embedded in the glass base, terminals mounted upon the glass base and connected with the leads, and a hot electrode carried by the inner ends of the leads.

4. An electric discharge device comprising a glass tube having one end open, a glass base arranged within the open end of the tube, a metal ring receiving the periphery of the glass base and having the glass base welded thereto, one end of the glass base projecting beyond the metal ring and having its material extending over the periphery of the ring for a short distance, the glass tube being welded to the ring and the projecting portion of the glass base, leads embedded in the glass base, tubular terminals receiving the outer end of the leads and engaging the glass base, and a hot electrode carried by the inner ends of the leads.

5. An electric discharge device comprising a glass envelope having an opening, a metal retainer, a glass base arranged within the metal retainer and welded to the same, leads embedded in the glass base, an electrode carried by the leads, the metal retainer forming a recess upon the outer side of the glass base, the metal retainer being arranged within the opening and welded to the glass envelope, an insulating disc inserted within the recess, and tubular terminals carried by the insulating disc and receiving the leads therein.

6. An electric discharge device comprising a glass tube having one end open, a metal retainer arranged within the open end of the glass tube and including spaced inner and outer rings, the outer ring being welded to the glass tube, a glass base arranged within the inner ring and welded to the inner ring, the inner ring forming a recess upon the outside of the glass base, leads embedded in the glass base, an electrode carried by the leads, an insulating disc arranged within the recess and having a press fit therein, and tubular terminals attached to the insulating disc and receiving the leads.

7. An electric discharge device comprising a glass tube having one end open, a substantially cylindrical metal retainer shell mounted within the open end of the glass tube and having substantially the same coefficient of expansion as the glass tube, the glass tube being welded to the metal retainer shell and the end of the glass tube extending substantially to the outer end of the retainer shell, a thick glass disc arranged within and welded to the metal retainer shell, stout leads embedded within the glass disc and extending beyond the inner and outer faces of the glass disc, tubular terminals receiving the outer ends of the leads, and an electrode carried by the inner ends of the leads.

8. An electric discharge device comprising a glass tube having one end open, a substantially cylindrical metal retainer shell mounted within the open end of the glass tube and having substantially the same coefficient of expansion as the glass tube, the glass tube being welded to the metal retainer shell and the end of the glass tube extending substantially to the outer end of the retainer shell, a thick glass disc arranged within and welded to the metal retainer shell and having its outer face substantially flat, stout leads embedded within the glass disc and being of substantially the same length and extending beyond the inner and outer faces of the glass disc, the

leads being spaced radially inwardly from the welded joint between the metal retainer shell and the glass tube, tubular terminals receiving the outer ends of the ends, and an electrode carried by the inner ends of the leads.

9. An electric discharge device comprising a glass tube having one end open, a metal retainer shell having substantially the same coefficient of expansion as the glass tube, said shell including an outer ring, an inner ring spaced from the outer ring and an end connecting the inner and outer rings, the retainer shell being mounted within the open end of the glass tube and the glass tube welded to the outer ring, a glass disc arranged within the inner ring and welded thereto, leads embedded in the glass disc and spaced radially inwardly from the inner ring, an electrode carried by the inner ends of the leads, and tubular terminals receiving the outer ends of the leads.
